FINISHING MOLDING FOR UPHOLSTERING

James I. Hamm, Fairfield, Conn., assignor to The Bridgeport Coach Lace Company, Incorporated, Bridgeport, Conn., a corporation of Connecticut

Application September 20, 1935, Serial No. 41,449

2 Claims. (Cl. 20—74)

This invention relates to new and useful improvements in finishing molding for upholstery or trimming in automobile bodies, furniture and the like.

5 An object of the invention is to provide a finishing molding including a reinforcing or stiffening strip comprising a flat body portion and a locking bead woven to the body portion along one edge thereof whereby the bead does not have to be separately sewed to the body.

10 Another object is to provide a finishing molding wherein the tack concealing flap is hinged to the body of the strip to fold freely relative thereto and wherein other means are provided for securing said flap in tack concealing position.

15 A further object is to provide an improved stiffening strip to be used in a finishing molding for upholstery.

20 Other objects and advantages will become apparent from a consideration of the following detailed description taken in connection with the accompanying drawing wherein a satisfactory embodiment of the invention is shown. However, it will be understood that the invention is not limited to the details disclosed but includes 25 all such variations and modifications as fall within the spirit of the invention and the scope of the appended claims.

In the drawing:

20 Fig. 1 is a perspective view showing a strip of finishing molding constructed according to the present invention;

35 Fig. 2 is a transverse sectional view through the improved molding and in full lines showing the parts before being secured and in dotted lines showing the molding as secured in place;

30 Fig. 3 is a transverse sectional view showing the molding in place;

40 Fig. 4 is a plan view of a section of a stiffening strip employed;

Fig. 5 is a sectional view taken substantially along the line 5—5 of Fig. 4; and

45 Fig. 6 is a view similar to Fig. 3 but showing a slightly modified construction.

50 Referring in detail to the drawing the improved finishing molding comprises a stiffening strip generally designated 10 and comprising a flat body portion 11 and a relatively thick or large diameter cord or bead 12 arranged at one edge of said body portion. The cord 12 may be of paper, fibre or other material, and the body 55 11 comprises fibrous warp strands 13, preferably of cotton, and stiffening cross or weft strands 14 interwoven with the warp strands and preferably in the form of relatively small diameter

pliable metal wire as shown. In the weaving of the stiffening strip 10 the weft or cross strands 14 are carried about the cord 12 as shown at 15 in Figs. 4 and 5 so that said cord is woven to the body of the strip and so does not require being 5 separately secured thereto as by sewing.

In making up the present molding a suitable covering material 26 has one edge portion 16 cemented or otherwise secured to the cord 12 in a manner substantially enclosing the same and such covering is carried under or along the rear side of the body 11 of the stiffening strip and cemented or otherwise secured thereto. At a point 17 spaced from the inner edge 18 of the stiffening strip the covering is started about a 15 core 19 and is continued over the outer and inner surfaces of said core so that the latter is completely enclosed. The covering is secured to the core in any suitable manner as with cement or the like and the edge portion 20 of the covering 20 has its inner surface cemented or otherwise secured to the inner surface of an intermediate portion 21 of the covering. The core 19 may be of rubber, paper, or of a fibrous or other material and includes along one longitudinal edge 25 portion a lip 22 which is also enclosed by the covering. The covering material may be of leather, oilcloth, artificial leather, a woven fabric, or other suitable material.

Core 19 together with the portion of the covering secured thereto comprises a tack concealing flap generally designated 23 and the flat portion 11 of the stiffening strip 10 together with the portion of the covering secured thereto comprises the body portion of the present molding. Flap 35 23 is hingedly connected with said body portion at 24 by a single layer of the covering material so that said flap is freely swingable from the full line position of Fig. 2 to the dotted line position of that figure. While this is the preferable 40 construction it will be apparent that the stiffening strip might be extended beyond or across the hinge portion 24 so that the flap 23 would not be freely swingable but would be folded only on bending of the wires of the stiffening strip. 45

When the flap 23 is in the dotted line position of Fig. 2 the bead comprising the cord 12 and the covering portion secured thereto may be folded over onto the lip portion 22 of the flap as suggested in Fig. 2. In folding the bead 12 to dispose it on the lip portion of the tack concealing flap the wires weaving or securing said bead to the edge portion of the body of the stiffening strip are bent about the free edge portion of the flap and these bent wires serve to secure the bead in 55

position locking the flap against the upper side of the body of the molding.

When the molding is being applied the flap 23 is left in an open position as shown in full lines in Fig. 2 so that access may be had to drive tacks 25 through the body portion of the molding. After the tacks are in place the flap is swung to the full line position of Fig. 3, which position is also shown by the dotted lines in Fig. 2 and being disposed at the upper side of the body of the molding covers or conceals the heads of the tacks. Next, the bead 12 is folded into place to overlie the lip portion 22 of the flap as shown in Figs. 1 and 3 and thereby secure the latter in tack 15 sealing position.

In the folding of the bead 12 the weft wires of the stiffening strip are bent and serve to maintain the bead 12, which may be termed a locking bead, in place securing the flap against casual movement. It will be noted that the portions of the weft strands which are bent in the folding of the bead 12 into locking position are not remote from the free edge of the bead and so serve to effectively secure the bead in its locking position, 20 the leverage on said locking bead being thus relatively short. The portions 20 and 21 of the covering together with the inner portion of the stiffening strip and the covering applied thereto form a lip-like portion 27 at the inner edge of the 30 molding.

It will also be noted in Fig. 4 that in the particular stiffening strip shown the wire weft strands 14 extend across and back on the same side of a pick which gives two parallel wires in the same 35 pick so I get double the number of wires to the inch of fabric over a fabric where there is only one wire per pick. This gives a stronger stiffening strip and one which has a greater holding effect in the finished molding as will be apparent. 40 This construction of strip is preferred but I am not limited thereto as other stiffening means may be used.

Fig. 6 shows a slightly different construction wherein the flat or body portion 11a of the stiffening strip is somewhat narrower than the corresponding portion 11 of the strip of Figs. 1, 2, and 3. The covering is also somewhat narrower in Fig. 6, and after leaving the inner edge of the 45 stiffening strip proceeds but a short distance to

provide a hinge portion 24a and is then carried about and secured to the core 19 forming therewith a flap 23a corresponding with the flap 23 previously described. The molding of Fig. 6 is used in the same manner as the molding in Figs. 1, 2, and 3 and differs therefrom only in that the lip-like portion 27 of the first figure is omitted. 5

Having thus set forth the nature of my invention, what I claim is:

1. A finishing molding comprising a flat body 10 including metal strands extending across the body, a bead disposed laterally of one edge of said body and about which said strands are looped to secure the bead to the body, a flexible covering about said bead and secured to a side of the body 15 and extending beyond the edge thereof opposite that at which the bead is located, a core at said opposite edge of the body, said extending portion of the covering enclosing the core and hinged connecting it to the body for free folding movement over the edge of the body onto the body to conceal tacks driven therethrough, and said metal strands adapted to be bent to permit the bead to be folded onto a portion of the core when the latter is in tack concealing position to lock it in 20 such position.

2. A finishing molding comprising a body portion adapted to be tacked to a support and including a stiffening strip having fibre warps and weft including pliable metal wires interwoven therewith, a cord extending along one edge about which the wires are looped to secure it to the strip, a separate flexible fibrous finishing covering enclosing said cord forming therewith a bead and extending across the under side of the strip 35 and secured thereto, said covering extending beyond the strip on the opposite side from the cord forming a flexible hinge portion adjacent the edge of the strip, a yieldable core enclosed by said covering on the opposite side of the hinge from 40 said stiffening strip and forming with said covering a flap foldable over onto the body portion to cover tacks therein, and said bead being foldable over onto and overlapping one edge of said flap by bending said wires inwardly of the bead 45 and retaining the flap over said body portion by the action of said wires.

JAMES I. HAMM.
